UNITED STATES PATENT OFFICE.

ARTHUR O. KNIGHT, OF WORCESTER, MASSACHUSETTS, ASSIGNOR TO WORCESTER OFFICE SUPPLIES COMPANY, OF WORCESTER, MASSACHUSETTS, A CORPORATION OF MASSACHUSETTS.

STAMP.

1,369,671.

Specification of Letters Patent. Patented Feb. 22, 1921.

Application filed April 3, 1920. Serial No. 370,997.

To all whom it may concern:

Be it known that I, ARTHUR O. KNIGHT, a citizen of the United States, residing at Worcester, in the county of Worcester and 5 State of Massachusetts, have invented a new and useful Stamp, of which the following is a specification.

The object of this invention is to provide a hand stamp, such as the usual one having 10 rubber type, with an identifying device so that the same can be easily identified and properly employed.

To this end, the invention consists of the arrangements hereinafter described and 15 illustrated in the accompanying drawing in which—

Figure 1 is a front elevation of a stamp with my improvement applied thereto;

Fig. 2 is a bottom view; 20 Fig. 3 is a partial cross sectional view; and

Fig. 4 is a perspective view showing sections of the parts making up the identifying device.

25 Referring to the drawings, and in detail— A designates the body of a stamp which is provided with an upwardly extending handle B and which has the usual rubber type on its bottom face.

30 A channel piece C, consisting of a metal strip having bent over sides, is secured to the front face of the body portion A by brads D, the heads of which project into the channel when the channel piece is secured thereby to the body portion.

35 E designates a card or plate having an identifying legend printed or stamped thereon; and F designates a strip of transparent material as celluloid. The pieces E and F are all of just the right length and 40 breadth to fit into the channel piece C, and when slid therein the brads will hold the same in position.

The card E and transparent piece F are 45 cut the same length as the channel piece I,

so that when the parts are in position the same will present an attractive and neat appearance.

In the manufacture of the device the channel piece is first secured to the body 50 portion A by the brads D, the heads of which remain in the channel piece at some little distance in from its ends. Then the card and the transparent piece are inserted in the channel piece. This can be easily 55 done as they can be slid some distance into the channel piece before they will have to pass by the head of a brad.

After the card and transparent piece are housed in the channel piece, the sides of the 60 channel piece are tapped with a hammer. This action will clamp the transparent piece and card down on the heads of the brads, and thus the parts will be locked in position. Thus the device can be quickly and easily 65 manufactured.

A stamp arranged this way can be easily identified and accurately used.

Having thus fully described my invention, what I claim and desire to secure by 70 Letters Patent is:—

A stamp comprising a body portion, a handle extending from the top thereof, type secured to the bottom thereof, a channel piece having bent over sides secured to the 75 front face thereof by brads, the heads of which remain in the channel, a card or plate having an identifying legend thereon and a strip of transparent material as celluloid placed in said channel piece, said bent over 80 sides clamping said card and transparent plate against the bottom of the channel piece and said brad heads also serving to hold the card and celluloid in position in the channel piece, the card and strip being 85 of the same length as the channel piece.

In testimony whereof I have hereunto affixed my signature.

ARTHUR O. KNIGHT.
